HONING DEVICE FOR SLICING BLADE

Orlando Garapolo, Chicago, Ill., assignor to Wilson & Co., Inc., a corporation of Delaware

Application June 6, 1956, Serial No. 589,745

9 Claims. (Cl. 76—85)

This invention relates to a honing device for slicing blades, and particularly to a device for honing the cutting edge of a spirally shaped blade, such as a bacon slicing knife, without removing it from its housing.

Bacon slicing knives operate at substantial speed, and the bacon must be sliced uniformly thin. Accordingly, the cutting edge of the blade must be kept constantly in proper condition for efficient slicing. Heretofore these blades have been honed by hand, but the curvature and the transverse angularity of the cutting edge have combined to make hand honing a slow and laborious process. In addition, a great degree of skill is required to properly hone an angular edge curved in the spiral shape of bacon slicing knives.

In accordance with the present invention a honing tool in the form of a pin is mounted at the angle required, and is held against the cutting edge of the blade by a mechanical device. No skill is required to hold the honing pin against the edge at the proper angle. Guide means for insuring proper alignment of the honing device is permanently secured to the blade housing frame out of the way of the knife. The guide means facilitates proper positioning of the honing device so that it may be applied quickly to the blade housing frame and readily removed after the edge of the slicing blade is properly honed.

The structure by means of which the above and other advantages of the invention are attained will be described in the following specification, taken in conjunction with the accompanying drawings, showing a preferred illustrative embodiment of the invention, in which:

Figure 1 is a front elevational view showing a knife rotatably mounted in a housing, with the honing device of the present invention detachably mounted on the blade housing frame;

Fig. 2 is a cross sectional view, taken along the line 2—2 of Fig. 1;

Fig. 3 is a fragmentary perspective view of the blade housing frame, with the guide bar for the honing device secured thereto;

Fig. 4 is a detail perspective view of a honing device embodying the invention;

Fig. 5 is a cross sectional view, taken along the line 5—5 of Fig. 1;

Fig. 6 is an enlarged fragmentary perspective view of the honing device;

Fig. 7 is an end elevational view of the honing device;

Fig. 8 is a cross sectional view, taken along the line 8—8 of Fig. 1, but omitting the blade housing frame; and

Fig. 9 is a cross sectional view, taken along the line 9—9 of Fig. 7, but showing the honing pin in engagement with the cutting edge of a slicing blade.

Referring to Fig. 1 of the drawings, the reference numeral 2 indicates a bacon slicing knife mounted on a rotatable shaft 3 adjacent the frame 4 of a suitable housing. A motor (not shown) rotates knife 2 in a vertical plane in clockwise direction, as seen in Fig. 1. The knife is shaped like a spiral so that its cutting engagement with

a slab of bacon fed transversely of the knife by any suitable mechanism is progressive from the initial engagement until the slice is completely severed. It will be understood that the word "spiral" is used generically, and that the honing device may be used with cutting blades of any shape. The knife is also curved in cross section, as shown in Figs. 8 and 9. The outer edge 5, formed by the intersection of angular surfaces 6 and 7 is very thin, and the surface 6 must be honed to keep the edge extremely sharp.

A guide bar 8 is rigidly secured to the housing frame 4 by screws 9. Guide bar 8 extends horizontally and its inner end is spaced from shaft 3 a distance approximately equal to the distance from shaft 3 to the portion of the cutting edge closest thereto. The thickness of guide bar 8 is less than the distance between cutting edge 5 and the front surface of blade housing frame 4 to prevent the guide bar from interfering with the rotation of slicing blade 2.

20 The honing device comprises a pair of honing plates 10 and 11, a honing tool or pin 12, a honing pin holder 13, a spring pressed plate 14, a center plate 15, a spacer plate 16, and a holding plate 17. Honing plates 10 and 11 are secured to plate 14 by screws 14' (Fig. 9). Plates 15, 16 and 17 are arranged with one end of each flush with the others and are rigidly secured together by means of screws 18. Plate 16 is shorter than plates 15 and 17 and provides a space between them beyond its inner end. The honing device is adapted to straddle one edge of housing frame 4 with the inner end of spacer plate 16 abutting the edge, and plates 15 and 17 adjacent opposite surfaces of the housing frame. Spacer plate 16 is slightly thicker than housing frame 4 to facilitate movement of the honing device relative to the housing frame 30 so that the honing device may be easily positioned. When the lower edge of center plate 15 abuts the upper edge of guide bar 8, and the inner end of spacer plate 16 abuts the peripheral edge of housing frame 4, the honing device is secured in place. A screw 19, threaded through holding plate 17, is tightened against the rear surface of housing frame 4 to secure the honing device in place. Screw 19 is preferably provided with a wing head 20 to facilitate manual turning of the screw.

25 Plate 14 is secured to center plate 15 by means of screws 21, 22 and 23. Plate 15 is provided adjacent one end with a threaded aperture 24 into which screw 21 is threaded. Plate 14 is provided with a smooth aperture 25 to receive the shank of screw 21. The front end of aperture 25 is counterbored, as indicated at 26, to receive the head 27 of screw 21. The bottom edge of the counterbored portion of aperture 25 limits outward movement of plate 14 relative to plate 15, but does not affect its inward movement. The inward movement of plate 14 is limited by the rear side of honing plate 10 or 11 35 which abuts the open end of the counterbored aperture.

30 Plate 15 is provided adjacent its opposite end with a threaded aperture 28 into which screw 22 is threaded. Plate 14 is provided with a smooth aperture 29 to receive the shank of screw 22. Screw 22 is longer than screw 21 and extends entirely through plate 14 with its head 30 abutting the front surface of the plate. Head 30 also functions as a stop member for honing pin holder 13, as hereinafter described.

35 As shown in Fig. 2, screws 23 are inserted through apertures 31 in plate 14 and are each threaded into an aperture 32 in plate 15. The front end of aperture 31 is counterbored, as indicated at 33, to receive the head 34 of screw 23. The rear end of aperture 31 is also counterbored, as indicated at 35, to receive one end of a coiled compression spring 36 which encircles the shank of screw 23. One end of spring 36 bears against plate 14 and the other end bears against plate 15 to keep these

members spaced as far apart as head 30 and counterbores 26 and 33 will permit. Spring 36 normally keeps plate 14 in its outermost position. Whenever plate 14 is moved inwardly because of some irregularity in the surface of the slicing blade, spring 36 immediately moves it back to its outermost position as soon as the irregularity is passed.

As shown in Fig. 6, plate 14 has a longitudinal channel 37 disposed along the center line of its front surface. The inner edges 38 and 39 of honing plates 10 and 11, respectively, are spaced from the edges of channel 37 to provide ledges 40 and 41 on opposite edges of channel 37. Inner edges 38 and 39 of the honing plates extend upwardly from the surface of plate 14 at converging angles. Plates 10, 11, 14, 15, 16 and 17 constitute a frame in which the honing pin holder 13 is slidably mounted. The side walls of honing pin holder 13 are straight at their lower portions which are adapted to fit in the bottom of channel 37, and are provided with shoulders 42 and 43 (Fig. 7) to seat on ledges 40 and 41. The side wall portions of the honing pin holder 13 above shoulders 42 are flared inwardly to fit against the inner edges 38 and 39 of the honing plates and to provide a sliding fit that will not permit removal of the honing pin holder from channel 37. Head 30 of screw 22 is positioned in channel 37 adjacent one end of the channel to prevent honing pin holder 13 from sliding out of the channel. Spring pressed plate 14 is considerably longer than plate 15 and, therefore, screw 21, which is positioned adjacent the end of plate 15 is spaced a considerable distance inwardly of the opposite end of channel 37. Accordingly, a separate screw 44 is threaded into plate 14 adjacent the opposite end from screw 22, and its head extends into channel 37 to prevent honing pin holder 13 from sliding out that end of the channel.

Honing pin holder 13 is provided with a handle 45 to facilitate sliding movement in channel 37 between screws 22 and 44. Handle 45 is provided with a reduced end 46 (Fig. 8) threaded into honing pin holder 13. Holder 13 is also provided with an angularly extending aperture 47 into which honing pin 12 is drive fitted. The honing pin is made of oil hardening tool steel, and is preferably provided with a medium straight knurl. Honing plates 10 and 11 are provided adjacent the side walls of channel 37 with smooth outer surfaces 48 and 49, respectively, against which the back edge 7 of bacon slicing knife 2 abuts when the front edge 6 is being honed. The angle of the honing tool or pin 12 coincides with the angle of surface 6 when surface 7 is flush against surfaces 48 and 49. The front edge of honing pin holder 13 projects outwardly beyond surfaces 48 and 49. The front surface of holder 13 to the left of honing pin 12, as seen in Fig. 8, is recessed, as indicated at 50, to provide clearance so that the back surface of knife 2 will abut the smooth surfaces 48 and 49 when the knife edge is being honed.

When the bacon slicing knife is to be honed, the honing device is pushed over the edge of housing frame 4 with plates 15 and 17 straddling the edge of the housing frame above guide bar 8. The honing device is then moved downwardly and inwardly until the lower edge of plate 15 is flush against the top edge of guide bar 8 and the inner edge of plate 16 abuts the peripheral edge of housing frame 4. Screw 19 is then tightened to hold the honing device against movement relative to the housing frame.

A detachable handle 51 is secured in either of two apertures 52 (Fig. 1) provided therefor, and knife 2 is manually rotated until the portion of cutting edge 5 that is closest to shaft 3 is adjacent the inner end of the honing device. The honing pin holder 13 is then slid in channel 37 until honing tool or pin 12 is flush against surface 6 of the knife. The operator holds handle 51 in one hand and handle 45 in the other. As he rotates knife 2 in a clockwise direction by manipulation of

handle 51 he holds honing pin 12 against the surface 6 while permitting it to move outwardly in accordance with the spiral curvature of the knife. Although the back side of the knife is generally smooth, it may have some slight irregularity. Springs 36 tend to keep honing plates 10 and 11 against the back surface of the knife, and if these plates are forced rearwardly by any irregularity in the back surface of the knife, springs 36 will return the honing plates to their proper position immediately after the irregularity has passed the surfaces 48 and 49. The knife edge is honed without removing the knife from its operative position. As soon as the honing operation is completed screw 19 is loosened, and the honing device is readily removed from the housing frame. The guide bar 8 does not interfere with the regular operation of the knife and may remain on the housing frame permanently.

Although I have described a preferred embodiment of the invention in considerable detail, it will be understood that the description thereof is intended to be illustrative, rather than restrictive, as many details may be modified or changed without departing from the spirit or scope of the invention. Accordingly, I do not desire to be restricted to the exact construction described.

I claim:

1. A honing device for a slicing blade rotatably mounted in a housing, said device comprising a guide bar rigidly secured to said housing, a frame detachably securable to said housing with one edge abutting said guide bar and one part abutting an edge of said housing, said frame including a honing plate on one side thereof, a holder slidably mounted in said frame adjacent said honing plate, and a honing tool mounted in said holder, said honing tool projecting from said holder angularly relative to the plane of said honing plate.

2. A honing device for a slicing blade rotatably mounted in a housing, said device comprising a guide bar rigidly secured to said housing, a plate secured to said housing with one edge abutting an edge of said guide bar, a spring pressed plate secured to said first mentioned plate, said spring pressed plate having its outer surface juxtaposed against the rear surface of said slicing blade, the outer surface of said spring pressed plate having a channel extending longitudinally therein, a holder slidably mounted in said channel, and a honing tool angularly mounted in said holder to engage the front surface of said slicing blade adjacent its peripheral edge.

3. A honing device for a slicing blade rotatably mounted in a housing, said device comprising a guide bar rigidly secured to said housing, a plate secured to said housing with one edge abutting an edge of said guide bar, a spring pressed plate secured to said first mentioned plate, the outer surface of said spring pressed plate having a channel extending longitudinally therein, a pair of honing plates secured to the outer surface of said spring pressed plate on opposite edges of said channel, said honing plates each having an outer surface juxtaposed against the rear surface of said slicing blade, a honing pin holder slidably mounted in said channel, and a honing pin angularly mounted in said holder to engage the front surface of said slicing blade adjacent its peripheral edge.

4. A honing device for a slicing blade rotatably mounted in a housing, said device comprising a guide bar rigidly secured to said housing, a plate secured to said housing with one edge abutting an edge of said guide bar, a spring pressed plate secured to said first mentioned plate, the outer surface of said spring pressed plate having a channel extending longitudinally therein, a pair of honing plates secured to the outer surface of said spring pressed plate on opposite edges of said channel, each of said honing plates having its inner edge spaced from the adjacent edge of said channel and its outer edge juxtaposed against the rear surface of said slicing blade, the inner edges of said honing plates extending upwardly at

converging angles, a honing pin holder slidably mounted in said channel, said holder having edges shaped to fit between said inner edges of said honing plates, and a honing pin angularly mounted in said holder to engage the front surface of said slicing blade adjacent its peripheral edge.

5. A honing device for a slicing blade rotatably mounted adjacent a housing and having a cutting edge spaced at varying distances from the axis upon which said blade is mounted, said honing device comprising a frame having a spring pressed plate and a honing plate rigidly secured to said spring pressed plate, a honing pin, means slidably mounted in said frame for supporting said honing pin in fixed angular relationship to said honing plate, means for detachably securing said frame to said housing with said honing plate in engagement with the rear surface of said slicing blade and said honing pin engageable with the front surface of said slicing blade adjacent its peripheral edge, and means to move said honing pin laterally relative to said honing plate to keep it in contact with said cutting edge as said slicing blade is rotated.

6. A honing device for a rotatably mounted slicing blade having a spirally curved cutting edge, said cutting edge being angular in cross section, a frame mounted adjacent the rear surface of said slicing blade, said frame including a spring pressed plate having a longitudinally extending channel in one surface thereof, a honing plate rigidly secured to said spring pressed plate, a honing pin holder slidably mounted in said channel, and a honing pin mounted in said frame at an angle coincident with the angularity of said cutting edge, said honing plate and pin being engageable with opposite surfaces of said spirally curved cutting edge throughout its rotational movement.

7. A honing device for a rotatably mounted slicing blade having a spirally curved cutting edge, means for rotating said blade, the front surface of said blade contiguous to said cutting edge being angular, a frame mounted adjacent the rear surface of said slicing blade, said frame including an undercut channel, a honing plate secured to one surface of said frame adjacent one edge

of said channel to engage the rear surface of said slicing blade, a honing pin holder mounted in said undercut channel, and a honing pin mounted in said holder, said honing pin extending from said holder at an angle equal to the angle of the angular surface of said blade, said honing pin holder being slidable in said channel to hold said honing pin in contact with said angular surface of said blade as said blade is rotated.

8. A honing device for a slicing blade rotatably mounted in a housing, said device comprising a frame 10 detachably securable to the housing, said frame including a honing plate engageable with one surface of said slicing blade, a holder mounted in said frame adjacent said honing plate, said holder being slidable longitudinally of 15 said honing plate, and a honing tool mounted in said holder, said honing tool projecting angularly beyond the outer surface of said honing plate to engage the surface of said slicing blade opposite the surface engaged by said honing plate.
9. A honing device for a slicing blade rotatably mounted in a housing on an axis extending transversely of said housing, a frame detachably fixed to said housing, said frame including a honing plate extending radially of 20 said axis, the inner end of said honing plate being positioned to engage one surface of said slicing blade along the portion of the cutting edge closest to said axis, said honing plate having sufficient length to engage the entire length of said cutting edge as said slicing blade is rotated, and a honing tool slidably mounted on said frame adjacent said honing plate to engage the opposite surface of 25 said slicing blade along its entire length as said slicing blade is rotated.
